PULVERIZER

George B. Ebersole, Akron, Ohio, assignor to The Babcock & Wilcox Company, Jersey City, N. J., a corporation of New Jersey

Application September 19, 1942, Serial No. 458,935

13 Claims. (Cl. 241—47)

The present invention relates to the construction and operation of pulverizers of the type having rolling grinding elements located between cooperating relatively movable grinding rings and particularly to pulverizers of the type described designed for pulverizing coal, cement materials and the like at moderate capacities and in which the pulverized material is removed from the pulverizer in suspension in a gaseous carrier medium, such as the pulverizer shown in the Schwartz U. S. Patent No. 2,275,595.

The general object of my invention is the provision of a pulverizer of the type described which is characterized by an improved construction and arrangement of the parts in the air entrance area of the pulverizer. A further and more specific object is the provision of an improved pulverizer construction for disposing of ungrindable portions of the material undergoing pulverization, such as the pyrites constituents of coal, with a minimum wear on the pulverizer parts. A further specific object is the provision of an improved pulverizer construction for preventing material from working inwardly between certain rotary and stationary parts of the pulverizer, and thereby increasing the load on the drive mechanism of the pulverizer.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described preferred embodiments of my invention.

Of the drawings:

Fig. 1 is a sectional elevation of a pulverizer constructed in accordance with my invention;

Fig. 2 is an enlarged sectional view of some of the parts shown in Fig. 1 at a different location;

Fig. 2 is a horizontal section taken on the line 3—3 of Fig. 2;

Fig. 4 is a fragmentary sectional elevation illustrating a modified construction; and

Figs. 5 and 6 are views similar to Fig. 4 illustrating further modifications.

The pulverizer illustrated has a substantially cylindrical sectional housing 10 having a base section 11 with a slightly conical bottom plate mounted on a foundation 12. The base section contains the pulverizer drive assembly including a horizontal pinion shaft 13 arranged to drive a vertical drive shaft 14 axially arranged in the

housing. The drive shaft 14 extends upwardly through bearings arranged in a base plate 15 forming the top of the base section 11. The upper section 16 of the housing is of substantially cylindrical form and detachably secured in the base section plate 15. The upper housing section encloses the grinding parts of the pulverizer, which comprises a drive yoke 17 of generally conical form keyed on the upper part of the drive shaft 14. An annular lower grinding ring 19 is supported on and keyed to the lower outer portions of the drive yoke. The upper face of the grinding ring 19 is shaped to form a track for a circular row of rolling grinding elements 20, preferably balls of wear resistant alloy steel. The balls 20 support an upper grinding ring 21 having a ball track formed in its lower face. An annular spider 22 mounted on the upper ring is provided with lugs 23 arranged in guides on the inner wall of the housing section 16 for preventing rotation, but permitting vertical movement, of the spider and upper grinding ring. A resilient grinding pressure is exerted downwardly on the grinding parts by coil springs 24 engaging the spider.

The material to be pulverized is supplied through a feed spout 25 to the inner side of the upper grinding ring and ball row and deposits on the inclined upper surface of the drive yoke 17, being distributed throughout the grinding area by the rotation of the drive yoke and associated parts. The material flows outwardly over the upper surface of the yoke and lower grinding ring, is pulverized between the relatively moving balls and grinding rings, and discharges at the outer edge of the lower grinding ring 19.

The pulverizer disclosed is of the air swept type having an annular stream of carrier air passing upwardly through the pulverizer grinding zone and through a material classifier 30 to the pulverizer outlet 31. The carrier air is normally preheated and supplied under pressure by a suitable forced draft fan to an annular wind box 32 surrounding the lower part of the housing section 16. The annular stream of carrier air passes into the pulverizer housing through passages hereinafter described, and upwardly through a Venturi-shaped throat passage 33 formed between the outer side of the lower grinding ring 19 and an annular throat plate 35 secured to the inside of the housing and shaped to provide a high velocity stream of air sweeping past the discharge side of the lower grinding ring, the flow areas and air velocities being proportioned to prevent any pulverized material within the designed density range from dropping through the throat and

clogging the entering air passages. The air stream does not prevent the downward discharge of relatively unpulverizable small size particles of high density, such as is present in the pulverization of coal having a high pyrites or sulphur content. In such cases the heavy particles tend to drop through the throat against the rising air stream and into the subjacent portion of the pulverizer. A portion of the throat ring is also provided with a segmental spring-pressed relief gate 35^a for the passage of any pieces of unpulverizable foreign material, such as tramp iron, and allowing the same to drop into the lower portion of the housing. At a point opposite the location of the relief gate 35^a, the base section of the housing is provided with a compartment 40 for the collection of such unpulverizable material. The compartment 40 communicates with the grinding zone through a small opening 41 in the housing base plate below which a slidable gate 42 is mounted and manually operated through a rack and pinion system 43 to open and close the opening 41.

In accordance with my invention the pulverizer parts are constructed to facilitate the elimination of unpulverizable material without excessive wear on the material contacted parts, such as tends to occur when sweeps or plows are mounted on the lower grinding ring for moving the unpulverizable material to the discharge opening 41. Such material would ordinarily drop through the air throat onto the upper surface of the base plate, and unless removed would tend to work its way into the space between the base plate and rotating lower grinding ring or yoke, increasing the frictional wear on those parts. Sulphur balls in this area are also highly objectionable as they tend to freeze the rotating parts to the base plate when the pulverizer is shut down and thereby increase the load on the drive mechanism when again starting up. This freezing of the parts is accentuated by the thermal contraction of these parts when no longer subject to the preheated air or the heat developed during the grinding operation.

In the construction illustrated in Figs. 1-3 the rotating drive parts and base plate are so constructed that any such action is minimized. For this purpose the drive yoke 17 is terminated radially short of the outer side of the lower grinding ring 19, and the latter provided with a depending annular skirt 50 extending downwardly beyond the outer edge of the yoke to a point having a slight clearance from the base plate 15. The lower end of the skirt projects outwardly in the form of a lip 51 to provide a surface on which material dropping into that area can be supported and carried around towards the discharge opening 41. The supporting action of the lip is facilitated by the relative arrangement of a circular series of segmental filler plates 55 located on the inclined bottom of the wind box and extending downwardly towards the skirt lip 51 to form a narrow annular slot or gap 56 therebetween. The plates 55 tend to direct any material depositing thereon downwardly onto the rotating lip. The gap 56 is enlarged immediately above the discharge opening 41 by shortening the corresponding plate 55, as shown in Fig. 1.

The depending annular skirt on the lower grinding ring has its inner side arranged at an angle to and spaced from the outer side of the drive yoke 17. This construction provides an upwardly tapering space 57 which is occupied by an upwardly tapering annular baffle ring 58 on the base plate 15 proportioned to form a narrow

annular inverted V-shaped space between the stationary and rotating parts. This baffle construction obstructs the movement of any material into the space between the bottom of the drive yoke and base plate.

The angular rotation of the lower grinding ring is indicated by the direction of the arrow in Fig. 3. Consequently the pulverized coal leaving the upper surface of the grinding ring tends to flow over the outer edge thereof at an angle to but in the same general direction as the rotation of the lower ring. The pressure drop through the throat section of the pulverizer can be appreciably reduced when the air from the wind box 10 enters the pulverizing zone in approximately the same direction as the flow of fuel. For this purpose adjoining segmental filler plates 55 are provided with curved vertical blade sections 60 and 61 relatively arranged thereon to form a circular series of outwardly tapering composite curved blades or vanes 62 forming passages 63 therebetween curving inwardly in the direction of rotation of the lower grinding ring. The vanes 62 terminate at their inner ends opposite posts 64, between 15 the plates 55 and forming spaced continuations of the pulverizer casing and the discharge ends of the air passages. With this vane arrangement the entering air is distributed about the circumference of the throat section and directed obliquely to the normal direction of pulverized material leaving the grinding zone, i. e. at an angle of approximately 45° thereto. Confining the entering air to the curving passages 63 facilitates the movement of the unpulverizable material 20 down the plates 55 and onto the tip 51, and thus to the discharge opening 41.

While in Figs. 1-3 the plates 55 forming the stationary seal ring for the grinding ring skirt lip 51 are formed integrally with the vanes 60 25 and 61, the seal ring can be separately formed, as shown at 70 in Fig. 4, and secured to the casing below the air entrance opening. A circular wear plate 71 is secured to the inner side of the seal ring. An annular slotted curved bottom is thus 30 formed for the space below the air throat 33, one side of the bottom being defined by the grinding ring skirt lip 51. The seal ring 70 is cut away above the discharge opening 41 to permit the material carried by the lip 51 to discharge thereto. 35 In this modification the baffle ring 58^a is separately formed and secured to the base plate 15 to provide a steeply inclined annular space between the baffle ring and grinding ring skirt.

In the modified constructions illustrated in 40 Figs. 5 and 6, the annular supporting lip 51^a is formed on a peripheral portion of the drive yoke 17^a which extends beyond the outer side of the grinding ring 19^a. The projecting portion can be integrally formed as shown in Fig. 5 or by a 45 circumferential band 75 welded to the periphery of the drive yoke, as shown in Fig. 6. A horizontally arranged seal ring 70^a is secured to the pulverizer casing opposite the lip 51^a in Fig. 5 and cooperates therewith to define the slotted bottom for the space below the air throat.

In the pulverizer constructions illustrated, the material to be pulverized is supplied to the inner side of the grinding elements and pulverized during its outward passage therethrough. The pulverized material flows over the outer edge of the lower grinding ring at an oblique angle thereto due to the rotation of the ring. The pulverized material is swept up by the annular air stream entering through the passages 63 and swirling 50 upwardly through the air throat, the material

laden air then passing upwardly to the classifier and pulverizer outlet. The particles of material not swept up by the air stream due to their size or density fall through the air throat into the air entrance area at the outer side of the lower grinding ring. These particles collect on the bottom of this section and are carried around by the lip formed on the lower grinding ring skirt or drive yoke until the recessed portion of the seal ring is reached and the particles permitted to fall into the discharge opening 41. The air stream swirling in the direction of rotation of the lower grinding ring aids the movement of these particles towards the discharge opening. The arrangement of the supporting lip on the lower grinding ring is especially advantageous as this member is normally made with a harder wearing surface than the yoke, with corresponding longer life, and because replacement of the ring due to excessive wear in the track area also restores the original lip outside diameter. With the described lip and seal ring constructions, the bottom of the pulverizer is kept comparatively clean of foreign material.

While in accordance with the provisions of the statutes I have illustrated and described herein the best forms of the invention now known to me, those skilled in the art will understand that changes may be made in the form of the apparatus disclosed without departing from the spirit of the invention covered by my claims, and that certain features of the invention may sometimes be used to advantage without a corresponding use of other features. In the claims, the word "air" is intended to generically cover any gaseous carrier medium suitable for removing pulverized material in the manner described.

I claim:

1. A pulverizer comprising a casing having an outlet for material-laden air at its upper end and enclosing a horizontally arranged rotary grinding ring, rolling grinding elements on said grinding ring, means for effecting relative movement of said grinding elements and ring, means for delivering material to be pulverized to the inner side of said grinding elements, means for directing a stream of air upwardly past the outer side of said grinding ring to sweep up pulverized material discharging therefrom including an air supply chamber opening to said casing at the outer side of said grinding ring and below the level of said grinding elements, a discharge opening for unpulverized material at the outer side of said grinding ring and adjacent said air entrance opening, and an outwardly projecting annular lip member at the outer side of and rotating with said grinding ring, said lip member having an upper surface portion horizontally arranged and in position to receive unpulverized material discharged from said grinding ring and carry said unpulverized material towards said discharge opening.

2. A pulverizer comprising a casing having an outlet for material-laden air at its upper end and enclosing a horizontally arranged rotary grinding ring, rolling grinding elements on said grinding ring, means for effecting relative movement of said grinding elements and ring, means for delivering material to be pulverized to the inner side of said grinding elements, means for directing a stream of air upwardly past the outer side of said grinding ring to sweep up pulverized material discharging therefrom including an air supply chamber opening to said casing at the

outer side of said grinding ring and below the level of said grinding elements, a discharge opening for unpulverized material at the outer side of said grinding ring and adjacent said air entrance opening, an outwardly projecting annular lip at the outer side of and rotating with said grinding ring shaped and arranged for carrying unpulverized material to said discharge opening, and means forming a stationary seal ring in the space between said lip and casing and cooperating with said lip to form a narrow annular slot therebetween.

3. A pulverizer comprising a casing having an outlet for material-laden air at its upper end and enclosing a horizontally arranged rotary grinding ring, rolling grinding elements on said grinding ring, means for effecting relative movement of said grinding elements and ring, means for delivering material to be pulverized to the inner side of said grinding elements, means for directing a stream of air upwardly past the outer side of said grinding ring to sweep up pulverized material discharging therefrom including an air supply chamber opening to said casing at the outer side of said grinding ring and below the level of said grinding elements, a discharge opening for unpulverized material at the outer side of said grinding ring and adjacent said air entrance opening, and a depending skirt on the outer side of said grinding ring having an outwardly projecting lip with an upper surface portion horizontally arranged and in position to receive unpulverized material discharged from said grinding ring and carry said unpulverized material to said discharge opening.

4. A pulverizer comprising a casing having an outlet for material-laden air at its upper end and enclosing a horizontally arranged rotary grinding ring, rolling grinding elements on said grinding ring, means for effecting relative movement of said grinding elements and ring, means for delivering material to be pulverized to the inner side of said grinding elements, means for directing an annular stream of air upwardly past the outer side of said grinding ring to sweep up pulverized material discharging therefrom including an air supply chamber opening to said casing at the outer side of said grinding ring and below the level of said grinding elements, a discharge opening for unpulverized material at the outer side of said grinding ring and adjacent said air entrance opening, a depending skirt on the outer side of said grinding ring having an outwardly projecting lip with an upper surface portion horizontally arranged and in position to receive unpulverized material discharged from said grinding ring and carry said unpulverized material to said discharge opening, and means forming a stationary seal ring in the space between said skirt and casing.

5. A pulverizer comprising a casing having a base plate and an outlet for material-laden air at its upper end and enclosing a horizontally arranged rotary grinding ring, rolling grinding elements on said grinding ring, an annular drive yoke superjacent said base plate and supporting said grinding ring, means for delivering material to be pulverized to the inner side of said grinding elements, means for directing a stream of air upwardly past the outer side of said grinding ring to sweep up pulverized material discharging therefrom including an air supply chamber opening to said casing at the outer side of said grinding ring and below the level of said grinding elements, a discharge opening for un-

pulverized material in said base plate at the outer side of said drive yoke and adjacent said air entrance opening, and an outwardly projecting lip on the outer side of said drive yoke, said lip having an upper surface portion horizontally arranged and in position to receive unpulverized material discharged from said grinding ring and carry said unpulverized material toward said discharge opening.

6. A pulverizer comprising a casing having a base plate and an outlet for material-laden air at its upper end and enclosing a horizontally arranged rotary grinding ring, rotary grinding elements on said grinding ring, an annular drive yoke superjacent said base plate and supporting said grinding ring, means for delivering material to be pulverized to the inner side of said grinding elements, means for directing a stream of air upwardly past the outer side of said grinding ring to sweep up pulverized material discharging therefrom including an air supply chamber opening to said casing at the outer side of said grinding ring and below the level of said grinding elements, a discharge opening for unpulverized material in said base plate at the outer side of said grinding ring and adjacent said air entrance opening, a depending skirt on the outer side of said grinding ring beyond said drive yoke, and a baffle ring on said base plate projecting upwardly into the space between said skirt and drive yoke to obstruct the inward flow of unpulverized material.

7. A pulverizer comprising a casing having a base plate and an outlet for material-laden air at its upper end and enclosing a horizontally arranged rotary grinding ring, rolling grinding elements on said grinding ring, an annular drive yoke superjacent said base plate and supporting said grinding ring, means for delivering material to be pulverized to the inner side of said grinding elements, means for directing an annular stream of air upwardly past the outer side of said grinding ring to sweep up pulverized material discharging therefrom including an air supply chamber opening to said casing at the outer side of said grinding ring and below the level of said grinding elements, a discharge opening for unpulverized material in said base plate at the outer side of said grinding ring and adjacent said air entrance opening, a depending skirt on the outer side of said grinding ring beyond said drive yoke and having means for carrying unpulverized material to said discharge opening, means forming a stationary seal ring in the space between said skirt and casing, and a baffle ring on said base plate projecting upwardly into the space between said skirt and drive yoke to obstruct the inward flow of unpulverized material between said base plate and drive yoke.

8. A pulverizer comprising a casing having an outlet for material-laden air at its upper end and enclosing a horizontally arranged rotary grinding ring, rolling grinding elements on said grinding ring, means for effecting relative movement of said grinding elements and ring, means for delivering material to be pulverized to the inner side of said grinding elements, means for directing an annular stream of air upwardly past the outer side of said grinding ring to sweep up pulverized material discharging therefrom including an air supply chamber and an air entrance opening from said chamber to said casing at the outer side of said grinding ring and below the level of said grinding elements, and

a circular series of curved vanes in said air entrance opening defining air passages curving inwardly in the normal direction of rotation of said grinding ring.

9. A pulverizer comprising a casing having an outlet for material-laden air at its upper end and enclosing a horizontally arranged rotary grinding ring, rolling grinding elements on said grinding ring, means for effecting relative movement of said grinding elements and ring, means for delivering material to be pulverized to the inner side of said grinding elements, means for directing an annular stream of air upwardly past the outer side of said grinding ring to sweep up pulverized material discharging therefrom including an air supply chamber opening to said casing at the outer side of said grinding ring and below the level of said grinding elements, a discharge opening for unpulverized material at the outer side of said grinding ring and adjacent said air entrance opening, a depending skirt on the outer side of said grinding ring having means for carrying unpulverized material to said discharge opening, and a circular series of curved vanes in said air entrance opening defining air passages curving inwardly in the normal direction of rotation of said grinding ring.

10. A pulverizer comprising a casing having an outlet for material-laden air at its upper end and enclosing a horizontally arranged rotary grinding ring, rolling grinding elements on said grinding ring, means for effecting relative movement of said grinding elements and ring, means for delivering material to be pulverized to the inner side of said grinding elements, means for directing an annular stream of air upwardly past the outer side of said grinding ring to sweep up pulverized material discharging therefrom including an air supply chamber opening to said casing at the outer side of said grinding ring and below the level of said grinding elements, a discharge opening for unpulverized material at the outer side of said grinding ring and adjacent said air entrance opening, a depending skirt on the outer side of said grinding ring having means for carrying pulverized material to said discharge opening, a circular series of plates in said air entrance opening forming a stationary seal ring surrounding said skirt, and a circular series of curved vanes on said plates defining air passages curving inwardly in the normal direction of rotation of said grinding ring.

11. A pulverizer comprising a casing having a stationary base plate and an outlet for material-laden air at its upper end and enclosing a horizontally arranged rotary grinding ring, rotary grinding elements on said grinding ring, an annular drive yoke superjacent said base plate and supporting said grinding ring, means for delivering material to be pulverized to the inner side of said grinding elements, means for directing a stream of air upwardly past the outer side of said grinding ring to sweep up pulverized material discharging therefrom including air supply means opening to said casing at the outer side of said grinding ring and below the level of said grinding elements, and upwardly projecting baffle means on said base plate arranged to obstruct the inward flow of solid material between said drive yoke and base plate.

12. A pulverizer comprising a casing having a stationary base plate and an outlet for material-laden air at its upper end and enclosing a horizontally arranged rotary grinding ring, rotary grinding elements on said grinding ring, an an-

nular drive yoke superjacent said base plate and supporting said grinding ring, means for delivering material to be pulverized to the inner side of said grinding elements, means for directing a stream of air upwardly past the outer side of said grinding ring to sweep up pulverized material discharging therefrom including an air supply chamber opening to said casing at the outer side of said grinding ring and below the level of said grinding elements, a discharge opening for unpulverized material in said base plate at the outer side of said grinding ring and adjacent said air entrance opening, and a baffle ring on said base plate projecting upwardly into the space below said grinding ring and arranged to obstruct the inward flow of unpulverized material between said drive yoke and base plate.

13. A pulverizer comprising a casing having a stationary base plate and an outlet for material-laden air at its upper end and enclosing a horizontally arranged rotary grinding ring, rolling grinding elements on said grinding ring, a cir-

cular drive yoke superjacent said base plate and supporting said grinding ring, means for delivering material to be pulverized to the inner side of said grinding elements, means for directing a stream of air upwardly past the outer side of said grinding ring to sweep up pulverized material discharging therefrom including an air supply chamber and an air entrance opening from said chamber to said casing at the outer side of said grinding ring and below the level of said grinding elements, a discharge opening for unpulverized material in said base plate adjacent to the outer side of said grinding ring and said air entrance opening, a depending skirt on the outer side of said grinding ring beyond said drive yoke and having means for carrying material depositing thereon to said discharge opening, and said base plate having an upper inclined surface arranged to obstruct the inward flow of material through the space below said skirt.

GEORGE B. EBERSOLE.
